BOX TOE CAP FOR SHOES

Fred N. La Chapelle, Beverly, Mass., assignor to
Sidney H. Huberman, Boston, Mass.

Application February 26, 1942, Serial No. 432,469

2 Claims. (Cl. 36—77)

1

This invention relates to shoe constructions in general and more particularly to laminated substitute materials for certain parts of shoes heretofore made of leather, paper, stiff felt, sheet metal, etc.

Objects of the invention include the provision of shoe parts which are desirably stiff in the finished shoe such as the box toe caps and counters, these parts being made of laminated material, such as plywood, which may be steamed or soaked to render it pliable but which stiffens upon drying; the provision of box toe caps for shoes made in substantially flat plywood sheets adapted to be steamed or soaked just prior to application thereof to the last so that the pulling over machine is capable of forming the plywood to the shape of the last; and the provision of plywood sheets cut to required form for box toes in flat condition, soaked or steamed to render them pliable and the glue between the laminations of less holding effect so that the individual laminations may slip relative to each other at least to a slight degree, said sheets then being ready for application to the last under the upper and hence capable of being formed to the shape of the last by the pulling over machine.

Other objects of the invention include the provision of flat plywood sheets shaped as required for box toes, skived from their edges inwardly, and bent or formed approximately at the skived area to form the box toes with a minimum of puckering or splintering of the plies at the bends.

Still further objects of the invention include the provision of died or cut out plywood sheets or panels skived deeply at their edges, soaked or steamed to render the plies flexible and the glue more or less liquid, said sheets or panels being then molded between dies to form a desired shape such as a pre-formed box toe for a "safety shoe," the principal bending occurring at the skived areas and the final product being in the form of a cup whose side walls are relatively thin and at substantially right angles to a thick bottom, the latter forming the top of the box toe and being strong enough to resist crushing under the impact of ordinary dropped articles, while if a very heavy article crushes the box toe, it can be easily sawed off the foot as is at present extremely difficult or impossible with metal box toes. In the pre-formed box toe it will be appreciated that the skived side walls will bear relatively heavy loads as they are arranged parallel thereto and need not be as thick or strong as the top of the box toe.

2

Other objects and advantages of the invention will appear hereinafter.

Reference is to be had to the accompanying drawings, in which

5 Fig. 1 is a plan view of a blank or panel for a box toe embodying the present invention;

Fig. 2 is an enlarged section of a blank or panel for a shoe part embodying the invention;

10 Fig. 3 is a section through a completed box toe; and

Fig. 4 is a section through a completed pre-formed box toe for a "safety shoe."

Box toe caps for shoes have been made of heavy leather but are usually formed from a felted 15 cotton and jute substance, and in "safety shoes" the box toe cap is made of sheet metal. It is the present purpose to provide a substitute for the felt and metal in the form of plywood or other laminated material and it is to be understood 20 that the invention is not limited to plywood but may also be applied to laminated fabrics, plastics, and combinations thereof with thin wood sheets. For purposes of clarity of disclosure of the invention it has been elected to illustrate it as applied to plywood.

Fig. 1 illustrates a box toe blank 10 or flat sheet which may be conveniently made from large plywood sheets by cutting along the edges 12, 14 thereof by means of a die cutter or the like. The 30 individual blanks are then skived or beveled at the edges as by a knife or rotating edging cutter, either by hand or by the use of rotary pattern or profile machines. In the case of box toe caps for dress shoes, the article is now complete with nothing further to be done until the actual making of the shoe, it being noted that the blank is thickest at its center as at 16 and gradually tapers to its edges 12 and 14 as is generally illustrated at 18 in Fig. 2. The individual laminations 40 are preferably very thin, and the entire cap is preferably little if any thicker than a conventional toe cap.

Just prior to the pulling over operation, the shoe upper 20 is peeled or folded back on itself 45 at the toe, over the last 22 and a blank 10 is inserted just over the canvas inner lining 24 with the edge 12 positioned transversely of the last at the base of the toe, and the toe edge 14 in position to be covered by the upper at the toe 50 edge thereof. The last is positioned in the pulling over machine and as the pinchers are operated to pull over the upper onto the sole of the last, the skived or angularly trimmed off edges of the blank are also pulled over and shaped to 55 the last as illustrated in Fig. 3. At the proper

point in the manufacture of the shoe staples or other fastening means 26 are used to secure the upper and the box toe cap to the skived edge 28 of the insole 30, thus completing the operation except for the subsequent wiping, as is conventional.

It will be seen that the box toe cap is bent over and shaped to the last at the trimmed off area 18, and that the maximum bend occurs generally where the blank is thinnest. In order to further provide against puckering, however, it is contemplated that the toe edge area of the blank may be scored as at 32, these cuts or scores stopping short of complete penetration of the blank in most cases, and providing for a lapping over of adjacent cut edges of individual plies in the blank during the pulling over operation, as clearly these areas will be under a buckling influence.

Ordinarily the plywood or similar laminated blank would be too stiff for the operations above described, and therefore it is contemplated that the operator will steam the blank thoroughly just prior to application thereof to the last, or that the blanks will be soaked or boiled in water. The steaming or soaking will render the laminated material sufficiently pliable for its use in the manner described, and also the glue holding the laminations will become somewhat liquified and the individual laminations will be enabled to slip relatively to each other during the bending so that cracking thereof is largely eliminated.

Fig. 4 illustrates a heavier pre-formed box toe cap 34 for workmen's "safety shoes" which are ordinarily provided with hard sheet metal caps. It has been found that these metal caps will prevent injury to the toes if a small object is dropped on them, but where a heavy object is dropped the cap bends inwards and clamps the toes preventing removal of the shoe and causing loss of venous flow so that the toes swell and become painful. These metal toe caps cannot be sawed off and often it is hours before the shoe can be taken apart. The laminated plywood or similar material toe cap here disclosed will stop small

objects from injuring the toes and in the case of crushing by a heavy object the cap can be quickly sawed off.

A thicker sheet of plywood or the like is used for box toe cap 34, and it is skived or trimmed to a greater degree than the dress shoe box toe, but in the same manner as hereinbefore described as to the dress box toe. The blank is steamed or soaked and is then pressed to the form shown in Fig. 4 between dies which may be heated to more quickly dry the toe cap. It will be apparent that the edges 36 which are bent are much thinner than the plane or slightly arched top portion 38, the latter being only very slightly affected by the dies. Edges 36 will obviously be located parallel to the force of impact loads and need not be as thick or strong as the top portion 38 which is substantially normal to the force of dropped articles. As in the case of the dress box toe cap, the individual laminations will slide relative to each other during the die forming operation due to the at least partial liquidity of the glue after the steaming or soaking operation.

Shoe counters and other stiff shoe parts can be made of the material and by the methods above outlined and it is desired to point out that the invention is not limited to box toe caps, although it has been found convenient to show the invention as applied to the caps merely for illustrative purposes.

Having thus described my invention and the advantages thereof, I do not wish to be limited to the details herein disclosed, otherwise than as set forth in the claims, but what I claim is:

- 35 1. A laminated box toe cap comprising a wooden cup-like element, the central portion of the element having a plurality of laminations and the rim of the element having a lesser number of laminations than the central portion.
- 40 2. A laminated box toe cap as recited in claim 1 wherein edges of the laminations are beveled to present a smooth surface.

FRED N. LA CHAPELLE.
